UNITED STATES PATENT OFFICE.

EDWARD J. BROOKS, OF EAST ORANGE, NEW JERSEY.

SNAP-SEAL.

No. 923,014.

Specification of Letters Patent. Patented May 25, 1909.

Application filed March 11, 1909. Serial No. 482,779.

To all whom it may concern:

Be it known that I, EDWARD J. BROOKS, a citizen of the United States of America, and a resident of East Orange, in the State of New Jersey, have invented a new and useful Improvement in Snap-Seals, of which the following is a specification.

This invention relates, in common with previous improvements, to self-fastening seals or "snap seals", as they are commonly termed, for use as substitutes for lead and wire seals and other press fastenable sealing devices to secure the doors of railway freight cars and for other like purposes. Examples of such snap seals are set forth in my specification forming part of United States Letters Patent No. 912534, dated February 16, 1909, and in my previous specification therein referred to.

20 The present invention is more particularly additional to the improvement in snap seals set forth in my specification forming part of said Letters Patent No. 912534.

25 The leading object of the present invention is to provide in a two-part snap seal, made wholly of sheet metal, for interlocking the shackle ends with each other within the seal part, as additional means for rendering the seal secure against being violated without detection.

30 Other objects will be set forth in the general description which follows.

The invention consists in certain novel combinations of peculiarly constructed parts, 35 and in an improved snap seal embodying such combinations or either of them, as hereinafter more particularly described and claimed.

30 A sheet of drawings accompanies this specification as part thereof.

Figures 1 and 2 are respectively face and edge views of the shackle of the improved seal shown flat excepting its permanent bends; Figs. 3 and 4 are respectively a top 45 view and a longitudinal section through the partly formed seal part; Figs. 5 and 6 are sectional edge views showing respectively the seal part and shackle as preliminarily united, and as they appear after the seal is 50 snap fastened; and Fig. 7 is a fragmentary perspective view of the interlocked shackle ends.

Like reference characters refer to like parts in all the figures.

55 The improved seal is composed of a flexible shackle, *a*, and a seal part, *b*, each formed

complete from a single piece of suitable sheet metal, that of the shackle being preferably the harder so as to be resilient, but by proper selection both parts may be made of one and 60 the same metal.

Of the respective shackle ends, 1 and 2, the former is constructed with a transverse corrugation, 3, and with a suitably bent catch portion, 4, of reduced width extending 65 beyond said corrugation. The other shackle end, 2, is constructed with a catch hole, 5, near its extremity and with a pair of spurs, 6 and 7, formed by making V-shaped incisions in the sheet metal and bending the 70 partly severed points outward on opposite sides. The face or both sides of the shackle may be provided with the customary permanent distinguishing marks, as illustrated by "BJERR-467896" in Fig. 1. 75

The seal part *b* is preferably and conveniently oval in shape, and includes a central label portion, 8, having embossed or printed distinguishing marks represented by "BJERR New York" in Fig. 3, surrounded 80 by a tubular portion, 9, shown in its completed form in Figs. 5 and 6, with its seam, 10, adjoining the edge of said label portion, and with its inlet hole, 11, and a pair of rigid inwardly projecting lips, 12 and 13, at the sides 85 of said inlet hole, located at the front or back of the seal part as may be preferred. Said corrugation 3 of the shackle *a* interlocks with the inturned edge or seam 10 of the seal part *b*, at the larger end of the tubular 90 rim 9, and its catch 4 extends beyond said corrugation within said tubular rim as shown in Figs. 5 and 6. The two parts of the seal are thus preliminarily united at the factory. 95

To obviate otherwise fastening the shackle end 1 to keep the catch 4 in effective position for the snap fastening operation, the shackle *a* is preferably given a substantially circular form as in Fig. 5 so that the strain thereon in the press fastening operation will not tend to move the catch 4 away from the inlet 11. 100

In the press fastening or sealing operation the extremity of the shackle end 2, after entering the inlet 11, interlocks with the catch 4; the shackle end 2 and catch 4 mutually yielding or flexing to a sufficient extent, and resuming their original forms by the resiliency of the metal, so that the catch 4 projects through the catch hole 5 in the fastened 110 seal as represented in Figs. 6 and 7.

Simultaneously, the spurs 6 and 7 pass the

- 5 lips 12 and 13, at the inlet 11, and springing apart after clearing the same afford additional security against the violation of the seal without detection, or, considering these 10 spurs as the primary fastening, the interlocking of the shackle ends with each other by means of said catch 4 and catch hole 5 afford such additional security as hereinbefore stated.
- 10 10 The shape of the seal part *b* may obviously be changed at will without affecting the operation of the seal; and other like modifications will suggest themselves to those skilled in the art.
- 15 15 Having thus described said improvement, I claim as my invention and desire to patent under this specification:
1. The combination, in a snap seal, of a sheet metal seal part constructed with a central label portion and with a tubular rim 20 having its seam adjoining said label portion and provided with an inlet hole, and a resilient shackle of sheet metal having one end constructed with a transverse corrugation permanently fastened in said seam and 25

a suitably bent snap catch extending beyond the same within said rim and with a catch hole adapted to interlock with said catch at its other end.

2. The combination, in a snap seal, of a 30 sheet-metal seal part constructed with a central label portion and with a tubular rim having its seam adjoining said label portion and provided with an inlet hole and inwardly projecting lips at the sides of said hole, and a resilient shackle of sheet metal having one end constructed with a transverse corrugation permanently fastened in said seam and a suitably bent snap catch extending beyond the same within said rim and with a catch 40 hole adapted to interlock with said catch at its other end and oppositely projecting spurs adjacent to said catch hole adapted to interlock with said lips, substantially as hereinbefore specified.

EDWARD J. BROOKS.
